UNITED STATES PATENT OFFICE.

PETER A. SCHAEFER, OF CINCINNATI, OHIO, ASSIGNOR TO THE UNITED STATES PLAYING CARD COMPANY, OF SAME PLACE.

DESIGN FOR A GAME-CHIP.

SPECIFICATION forming part of Design No. 34,593, dated May 28, 1901:

Application filed May 24, 1900. Serial No. 17,891. Term of patent 14 years.

To all whom it may concern:

Be it known that I, PETER A. SCHAEFER, a citizen of the United States, residing at Cincinnati, Hamilton county, State of Ohio, have 5 invented and produced a new and original Design for Game-Chips, of which the following is a specification.

The leading feature of my design is a chip to be employed in games of cards and the like; 10 and the design consists in a game-chip having the ornamentation of a lion rampant grasping a truncheon, all of which is inclosed in a circle, as shown in the accompanying drawings, to wit:

Figure 1 is a face view of the game-chip, and 15 Fig. 2 is an edge view thereof.

a is a chip bearing thereon in a color or tint contrasting in color with the body of the chip the following representation: a lion rampant grasping a truncheon, as indicated at 1, 20 and a circular figure indicated at 3.

What I claim is—

The design for a game-chip, substantially as herein shown and described.

PETER A. SCHAEFER.
